UNITED STATES PATENT OFFICE.

ALFRED W. REISER, OF TOLEDO, OHIO, ASSIGNOR TO THE WESTERN GAS FIXTURE COMPANY, OF TOLEDO, OHIO, A CORPORATION OF OHIO.

DESIGN FOR A GLASS SHADE FOR ELECTRIC LIGHTS.

48,126.

Specification for Design.

Patented Nov. 9, 1915.

Application filed June 7, 1915. Serial No. 32,751. Term of patent 3½ years.

To all whom it may concern:

Be it known that I, ALFRED W. REISER, a citizen of the United States, and residing in Toledo, in the county of Lucas, State of Ohio, have invented a new, original, and ornamental Design for a Glass Shade for Electric Lights, of which the following is a specification, reference being had to the accompanying drawing, forming a part thereof.

Figure 1 is a plan view of the glass shade for electric lights, showing my design, and Fig. 2 is a side view of the design shown in Fig. 1.

I claim,—

The ornamental design for a glass shade for electric lights as shown.

ALFRED W. REISER.
